TOY AND BALL CASING

Edna C. Bailliere, Warren, Ohio

Application January 10, 1942, Serial No. 426,265

5 Claims. (Cl. 273—58)

1

The invention relates to a casing for a ball, a toy animal or bird, and in fact a casing of any desired form or figure. Particularly the casing is formed from a pair of flat pieces of flexible material such as rubber which are secured together preferably at or adjacent their outer edges. The flat pieces in the preferred construction have holes going therethrough which increase lateral flexibility or distendability of the casing. An inflatable bladder is inserted within the casing which distends the casing and the casing supports the bladder. The invention also relates to the combination of the novel casing and inflatable bladder.

An object of the invention is to construct a wholly flat casing, which is to receive an inflatable bladder, formed from flat members of flexible material stitched or otherwise secured together at or adjacent the outer edges thereof, and having means which preferably are holes through the casing to increase the lateral distendability thereof.

Another object of the invention is to construct a ball casing of a pair of flat members or blanks of flexible material having holes provided therethrough to increase lateral flexibility or distendability thereof and so disposed that a substantially spherical ball results when a bladder is inflated therein.

A still further object is to construct an inflatable figure utilizing a wholly flat casing but which has a substantial lateral distendability.

Another object of the invention is to construct an inflatable ball from a casing formed of a pair of flat disks of rubber or the like which are stitched or otherwise secured together at their outer periphery and having holes so positioned that the ball assumes a substantially spherical form when the bladder is inflated therein.

Another object is to form a casing having substantial lateral distendability which is inexpensive, easily made and attractive.

Other objects of the invention will be more apparent from the following description taken in connection with the accompanying drawing in which

Figure 1 is a partial view of a casing having holes therein of one form of pattern or design.

Figure 2 is a partial view of another casing having holes therethrough such that a substantially spherical ball is formed when a bladder is inflated therein.

Figure 3 is a side view of the casings of Figures 1 and 2.

2

Figure 4 is a view showing the casing of Figure 2 with an inflated bladder therein.

Figure 5 is a partial section of an inflated ball with the casing turned inside out so that the ridge is inside of the casing.

Inflatable balls of spherical shape have been made by forming a casing of many pieces which are stitched together such that the normal or relaxed shape of the casing is spherical. The cutting of many pieces and the cementing or stitching of these many pieces together involves considerable labor and expense. Figures of other shapes or forms have been similarly made. The casing of the invention on the other hand is formed of flat pieces of flexible material such as rubber which are sewed or otherwise secured together and in the case of most balls and figures the flat members or blanks are secured together at or adjacent their outer edges. If the shape desired is that of a ball a pair of circular disks are formed which may then be stitched together at their periphery and preferably holes are punched through the disks which increase the lateral distendability of the casing so that a ball is formed when a bladder is inflated therein. It is clear that the casing may take the form of birds, animals, or any other desired shape.

The casing illustrated in Figure 1 is formed by cutting a pair of circular disks 10 of flexible material such as rubber, which are sewed together at their periphery in any suitable fashion by the stitching 11 so as to leave the central portions of each disk separable from the other. Holes 12 are punched or otherwise provided through the disks to increase the lateral distendability thereof. Preferably the size of the holes in the disks decrease in diameter towards the center thereof. The holes 13 being smaller than the holes 12, the holes 14 being still smaller, and the holes 15 adjacent the center, may be the smallest. With the pattern of holes disclosed in Figure 1, a ball is formed when a bladder is inflated therein which is slightly flat at the ends.

A central hole 16 may be provided in one of the disks for access to the valve of the bladder to be inserted between the two disks. The hole 16 or any other hole may be used for this purpose or an opening between the disks through the stitching may be provided.

In Figure 2, the disks 20 are like the disks 10 which are also shown to be sewed together by stitching 21 at the periphery thereof. The pattern of holes in the casing of Figure 2 is different than that shown in Figure 1. The holes 22, 23 and 24 are provided to increase the lateral dis-

tendability of the disks. Since a lesser amount of distendability is required in the outer portion of the disks, these holes may be relatively widely spaced. The holes 25 and 26 increase the lateral distendability of the ball at a point adjacent to and just within a circle at the center of the disks which circle has a diameter approximately half of the full diameter of the disks so that upon inflation of a bladder therein, the resultant form is spherical or very nearly so. 10

The holes extending through the flat blanks or members remove material which otherwise would resist lateral distendability when a bladder is inflated therein or to express it in another way the holes leave portions of the casing which 15 resist expansion in the casing wherever and to whatever extent such resistance is desired. It is not necessary to have holes through the blanks in order to decrease resistance to lateral distendability or bring about an increase in lateral 20 distendability and other means or provision functioning in the same manner to reduce resistance and thereby to increase lateral distendability is contemplated. The pair of flat members, or at least one thereof, has recesses which leave portions of the member with greater distendability than other portions which recesses in the 25 form illustrated are holes extending through the member.

The area of greater strain upon the disks when a bladder 30 is inflated therein comes at, or adjacent, the circle midway between the outer periphery and the center of the disks. At this point the disks should have sufficient strength or resistance by providing ample material between the holes 13 and between the holes 14 as in the casing of Figure 1 and between the holes 24 in the casing of Figure 2. Where it is not desired to produce a ball which is spherical or substantially so, any design or pattern of holes may 35 be utilized. By using a bladder of a different color from that of the casing, an attractive ball or other figure is produced. The circular holes in the casing stretch into many different shapes depending upon the spacing between holes and the general pattern.

The casing of a toy or ball of the invention may utilize a bladder of relatively heavy wall thickness. A novel effect however, may be produced by using a bladder which is relatively thin and the holes relatively large such as the holes 12 and 13. When the bladder 30 is inflated in the casing, the bladder bulges outwardly in the holes as illustrated in Figure 4. Other novel effects can be produced by using bladders having portions projecting through the holes which portions also inflate upon blowing up of the bladder. For example if a casing of an animal form is used, four legs upon a bladder may be projected through holes which inflate to form legs which support the figure.

A wide variety of bladders may be utilized with the casing. The bladder may have a valve of any simple kind for retaining the air therewithin. The bladder may also be a common inexpensive balloon having a cylindrical neck for inflating the same. Where this style of bladder is used, the neck may be projected through the center hole such as the hole 18 in Figure 1 or 27 in Figure 2. When the bladder is inflated the end of the neck may be tucked through another hole between the casing and bladder to retain the air in the bladder.

Ordinary heavy sewing thread may be used to secure or stitch the pair of flat flexible casing blanks together at their outer edge. Such stitching is loose enough and when coupled with the flexible material of the casing permits some increase in the diameter or size of the inflated ball or figure over the diameter of the disks or blanks. If desired the casing may be turned inside out whereupon the ridge, shown on the outside in Figure 4, is upon the inside of the ball or figure and the outer surface is smooth or carries a slight groove. Preferably a uniform or symmetrical distribution of the holes or means to decrease the resistance to lateral distendability of the flat members results in a more attractive ball or toy.

This invention provides an improvement in a toy and ball casing. It is understood that various modifications in structure, as well as changes in mode of operation, assembly, and manner of use, may and often do occur to those skilled in the art, especially after benefitting from the teachings of an invention. This disclosure illustrates the preferred means of embodying the invention in useful form.

What is claimed is:

1. A casing adapted to receive an inflatable bladder comprising a pair of flat members of elastic material which form a complete casing having the form of a toy or ball, means securing the flat members together, and at least one of the flat members having recesses therein thereby providing portions which resist expansion to a greater extent than other portions thereof to control the lateral distendability of the casing.

2. A casing adapted to receive an inflatable bladder comprising a pair of flat members of flexible material and having a desired form, means securing the flat members together at their outer edges, and the flat members having holes therein of a desired pattern to increase the lateral distendability of the casing.

3. A ball casing adapted to receive an inflatable bladder comprising a pair of circular flat members of flexible material, means securing the flat members together at their periphery, and the flat members having uniformly distributed holes therein to increase the lateral distendability of the flat members.

5. A ball casing adapted to receive an inflatable bladder comprising a pair of circular flat members of flexible material, means securing the circular flat members together at their periphery, the circular flat members having uniformly distributed holes therein to increase the lateral distendability of the flat members, and the material being substantially reduced between holes adjacent to and within a circle having approximately half the diameter of the flat members.

6. A ball casing adapted to receive an inflatable bladder comprising a pair of circular flat members of flexible material, means securing the flat members together at their periphery, and the flat members having circularly disposed widely spaced holes therethrough in the outer half of the flat members and closely spaced holes adjacent to and within a circle having approximately half the diameter of the flat members to increase the lateral distendability of the casing and form a substantially spherical ball when a bladder is inflated within the casing.
